UNITED STATES PATENT OFFICE.

BOHUMIL SCHVERMA, OF TWO RIVERS, WISCONSIN.

MOLD.

1,113,142.

Specification of Letters Patent.

Patented Oct. 6, 1914.

Application filed March 24, 1914. Serial No. 626,933.

To all whom it may concern:

Be it known that I, BOHUMIL SCHVERMA, a citizen of the United States, residing at Two Rivers, in the county of Manitowoc and State of Wisconsin, have invented certain new and useful Improvements in Molds, of which the following is a specification, reference being had to the accompanying drawings.

10 This invention relates to an improved mold and has for its primary object to produce a device of this character whereby building blocks may be expeditiously molded.

15 The invention has for a more particular object to provide a mold including side and end plates, and a simple and novel frame structure to support said plates in their erect positions and hold the same against movement by the pressure of the plastic material upon the same, said frame including a plurality of expandable sections, and means for expanding said sections whereby the frame may be removed.

20 The invention has for another object to generally improve and simplify the construction of molds of the above character, and to enable the same to be produced at comparatively small manufacturing cost.

25 With the above and other objects in view as will become apparent as the description proceeds, the invention consists in certain constructions, combinations and arrangements of the parts that I shall hereinafter 30 fully describe and claim.

35 For a full understanding of the invention, reference is to be had to the following description and accompanying drawings, in which—

40 Figure 1 is a side elevation of a mold for building blocks constructed in accordance with my invention. Fig. 2 is an end view thereof. Fig. 3 is a top plan view. Fig. 4 is a section taken on the line 4—4 of Fig. 3. Fig. 5 is a detail vertical section taken on the line 5—5 of Fig. 1. Fig. 6 is a horizontal section taken on the line 6—6 of Fig. 1.

45 Referring in detail to the accompanying drawings, 5 designates the side plates of the mold form and 6 the end plates thereof. These plates are adapted to be arranged upon a suitable base or platform indicated at 7, to define a rectangular form. Each of said plates is provided upon its outer face

and adjacent each of its ends with a vertically disposed cleat 8 provided adjacent its upper end with a shoulder 9. To the inner sides of the end plates 6 of the mold, the substantially semi-cylindrical form members 10 are secured. A cylindrical form member 11 is centrally arranged upon the base between the semi-cylindrical end members 10, said member preferably consisting of circular end blocks or heads 12 connected by a sheet metal cylinder 13. The block 12 in the upper end of this form member is provided with a central opening to receive a plug 14, said block also having a second opening 15 extending transversely therethrough. This block 12 projects above the upper end of the sheet metal cylinder 13 whereby the same may be easily removed when the plastic material has set.

50 In order to retain the several mold plates in their erect positions, I have devised a very simple and novel construction of holding frame therefor. This frame includes an upper rectangular member 16. To the longitudinal side bars and the transverse end bars of this frame member, the expandable sections 17 and 18 respectively are hingedly connected along their upper edges as indicated at 19. To the ends of the upper bar of each of these movable frame sections, the posts or uprights 20 are secured, the lower ends thereof being connected by the bars 21. The ends of these lower bars are formed with rectangular plates or enlargements 22, each having an opening 23 formed therein. A block 24 is secured to each of the uprights 20 on its outer face, and these blocks are provided in one of their side faces with obliquely inclined grooves 25, for a purpose which will hereinafter appear.

55 To the ends of the upper frame member 16, the transverse bars 26 are rigidly secured. Vertically disposed rods 27 are movably mounted in the ends of these bars and to the upper ends of said rods, the outer ends of the levers 28 are pivotally connected. These levers are fulcrumed intermediate of their ends upon the standards 29 fixed upon the bars 26, and one of said levers is preferably bifurcated as at 30 to receive the inner end of the other lever. A hand grip 31 is mounted upon each of the bars 26 below the engaged ends of the levers 28. The lower

ends of the vertically movable rods 27 are formed with enlargements 32. These enlargements are provided with integrally formed lugs or projections 33 which extend 5 at right angles to each other and loosely engage in the grooves 25 formed in the contiguous blocks 24 on the end and side members respectively of the frame. The vertical rods 27 are connected and braced by means 10 of the bars 34. It will be observed that the rods 27 project below the enlargements 32 and are formed with tapering conical terminals 35 which are adapted to enter the coinciding openings 23 in the engaged plates 15 22 on the ends of the bars 21, whereby said frame sections will be securely held against relative movement when the mold is set up in condition for use.

In the use of my improved mold, the side 20 and end plates together with the form members are properly arranged upon the platform or base 7. The operator engages the palms of the hands upon the inner ends of the levers 28, and grasps the bars 31 with 25 the fingers. By exerting a downward pressure upon the levers, it will be obvious that the rods 27 are thereby drawn upwardly and the lugs 33 moving in the groove 25 force the side and end sections of the frame 30 outwardly so that said frame may be moved downwardly over the mold form. Upon the release of pressure upon the levers, the frame sections return to their normal positions, and engage against the vertical 35 cleats 8 upon the ends of the mold plates. The upper rectangular frame member 16 rests upon the shoulders 9 formed upon the upper ends of said cleats. The lower ends 40 of the vertical rods 27 being engaged in the openings 23 effectually hold the frame sections against outward spreading movement when the plastic material is poured into the mold between the side and end plates thereof. After the cement or other material has 45 properly set, the outer expandible frame may be readily removed in the manner above stated and the side and end plates together with the mold forms removed from the molded structure. As shown in the accompanying drawings, it will be seen that the 50 mold cement block is provided with a central opening and semi-circular grooves or channels in its end faces, so that when the blocks are assembled in a building wall, 55 the same will form a plurality of air passages therethrough. The central cylindrical mold form may be readily removed by disposing the plug 14 through the transverse 60 opening 15 provided in the block 12 of said member. By grasping the ends of this plug which project beyond the opposite sides of the mold member and turning said member, the same may be loosened from the plastic 65 material.

65 From the foregoing description taken in

connection with the accompanying drawing, it is believed that the construction, manner of operation and several advantages of my invention will be clearly and fully understood.

70 By the provision of the holding frame for the mold plates, made up of a plurality of expandible sections, the molding of the building blocks may be greatly facilitated.

75 The device as a whole is very simple in its construction, highly durable and efficient in practical use and may be manufactured at small cost.

80 While I have shown and described the preferred construction and arrangement of the several elements employed, it will be obvious that the invention is susceptible of considerable modification therein and I therefore reserve the privilege of resorting to all such legitimate changes as may be 85 fairly embodied within the spirit and scope of the invention as claimed.

Having thus described the invention, what is claimed is:

1. In a mold, side and end plates, a frame 90 including expandible side and end sections to engage the respective mold plates, means for simultaneously moving said frame sections outwardly with respect to each other, and means on said frame sections with 95 which said last named means co-operates to lock the frame sections against such relative movement, in their applied positions.

2. In a mold, side and end plates, a frame 100 including a rectangular member, movable side and end sections mounted upon said member to engage the respective mold plates, manually operable means mounted upon said member and engaging means upon said frame sections to lock said sections against relative movement, and additional means upon said frame sections with 105 which said manually operable means co-operates to move said frame sections outwardly from the mold plates.

110 3. In a mold, side and end plates, cleats secured to the outer faces of said plates provided with shoulders at their upper ends, a frame including a rectangular member adapted to engage said shoulders, relatively 115 movable frame sections mounted upon said member for engagement with the respective mold plates, manually operable means mounted upon the ends of said frame member, and means carried by the frame sections with which said manually operable means co-operates to move said frame sections outwardly from the mold plates whereby the latter may be removed.

120 4. In a mold, side and end plates, cleats secured to the outer faces of said mold plates provided with shoulders upon their upper ends, a frame including a rectangular member adapted to rest upon said shoulders, relatively movable frame sections 125 130

hingedly mounted upon said member for engagement with the respective mold plates, vertically movable rods mounted upon the corners of said rectangular member, blocks secured to the ends of each of said movable frame sections, each of said blocks being provided with an obliquely inclined groove, lugs on the lower end of each of said rods projecting at right angles to each other for engagement in the grooves of contiguous blocks, and means for moving said rods to force the frame sections outwardly with respect to each other away from the mold plates whereby the latter may be removed.

5 10 15 20 25 30 35 40

5. In a mold, side and end plates, cleats secured to the outer faces of said plates and provided upon their upper ends with shoulders, a frame including a rectangular member adapted to rest upon said shoulders, relatively movable frame sections hingedly mounted upon said member for engagement with the respective mold plates, blocks secured upon the ends of each of said frame sections, each block being provided with an obliquely disposed groove therein, plates carried by the frame sections each having an opening, the openings in the contiguous plates registering with each other when the frame sections are in their normal positions, vertically movable rods mounted upon the ends of the frame member at the corners of the frame, the lower ends of the respective rods being engaged in said coinciding openings to lock the frame sections against relative movement, lugs carried by said rods engaging in the inclined grooves of the contiguous blocks on said frame sections, and manually operable means for moving the rods at opposite ends of the frame member upwardly to move said frame sections outwardly with respect to each other away

from the mold plates whereby the latter may be removed.

6. In a mold, side and end plates, a frame member, clamping sections pivotally mounted upon said frame member for swinging movement, and means carried by said frame member and coöperating with said sections to swing the same into or out of clamping engagement with the mold plates.

45 50 55 60 65 70 75

7. In a mold, a plurality of mold plates, a frame including a body member, depending frame sections pivotally mounted at their upper edges upon said body member for swinging movement, manually operable means mounted upon the frame member and coöperating with said sections to swing the same into or out of clamping engagement with the respective mold plates, and means engaged by said last named means to lock the frame sections in clamping engagement with the mold plates.

8. In a mold, side and end plates, a frame including a horizontally disposed body member, depending frame sections mounted for swinging movement upon said body member, manually operable means mounted upon the opposite ends of said body member and coöperating with means on the contiguous ends of said frame sections to swing said sections into or out of clamping engagement with the mold plates, and means adapted to be engaged by said last named means to lock said frame sections in clamping engagement with the mold plates.

In testimony whereof I hereunto affix my signature in the presence of two witnesses.

BOHUMIL SCHVERMA.
